UNITED STATES PATENT OFFICE.

EDWARD W. ROBINSON, OF SAVANNAH, GEORGIA, ASSIGNOR, BY MESNE ASSIGNMENTS, TO INTERNATIONAL BARREL COMPANY, OF SAVANNAH, GEORGIA, A CORPORATION OF GEORGIA.

BARREL.

1,087,138.

Specification of Letters Patent.

Patented Feb. 17, 1914.

Application filed November 9, 1910. Serial No. 591,505.

To all whom it may concern:

Be it known that I, EDWARD W. ROBINSON, a citizen of the United States, residing in Savannah, Georgia, have invented certain 5 Improvements in Barrels, of which the following is a specification.

My invention relates to barrels composed of staves interwoven with properly spaced pairs of wires which take the place of the 10 usual hoops for retaining the staves in proper relation to one another, and my invention relates particularly to a barrel of this type intended for the storage and transportation of powdered or granular material 15 and technically known as a "slack" barrel in contradistinction to what is technically known as a "tight" barrel, which is intended for the storage and transportation of liquids.

20 The object of my present invention is to so construct the barrel as to prevent leakage of powdered material therefrom. This object I attain in the manner hereinafter set forth, reference being had to the accompanying drawing, in which—

Figure 1 is a side elevation of a barrel constructed in accordance with my present invention; Fig. 2 is a vertical section of one 30 end of the barrel with the head inserted therein; Fig. 3 is a sectional view of the head as it appears when detached from the barrel; Fig. 4 is a sectional plan view of part 35 of the barrel, on the line *a—a*, Fig. 1; Fig. 5 is a transverse section of part of the barrel on the line *b—b*, Fig. 4; Fig. 6 is a perspective view of the retainer for the twisted ends 40 of the wires, and Fig. 7 is a similar view of a modified form of said retainer. Figs. 4, 6 and 7 are on a larger scale than Figs. 1 to 45 3, inclusive, and Fig. 5 is on a still larger scale.

The barrel is composed of staves 1 which are preferably narrower at the ends than at the center so that when the staves are drawn 50 together until their edges meet the barrel will present the desired bilged form, the edges of the staves being beveled to insure the close fitting of the same.

The staves are confined in position by as 55 many pairs of wires 2 as it may be desired to employ, each stave being inserted between the wires of each pair and the latter being twisted together between the staves which are mortised at each edge, as shown 55 at 3 in Fig. 4, in order to receive these

twisted portions of the wires, said mortises being so proportioned in respect to the size of the wires that the twisted portions of the latter between the staves will snugly fill the openings formed by the coinciding mortises 60 of the adjoining staves, as shown in Figs. 4 and 5 and will, therefore, effectually prevent leakage of the contents of the barrel at these points even although such contents are in finely powdered form, such as flour or 65 cement. To further aid in the attainment of this object the wires are twisted under considerable tension and bite into or indent the staves at the bases of the mortises, thus insuring the extension of the twisted portions 70 of the wires into close contact with said bases, as also shown in Figs. 4 and 5, and the successive twists are all in the same direction, consequently a twist once completed is maintained tight, whereas if the 75 successive twists were in reverse directions a following twist would tend to loosen the preceding one, and would therefore interfere with the holding of the staves in the desired close relation to one another. 80

The distance between the top and bottom of each mortise should be such that when the wires are twisted together in the rear of a previously inserted stave they will all bite into said top and bottom edges of their respective mortises, and when a succeeding stave is pushed up into contact with a previously inserted one the top and bottom faces of the mortises in said stave will be indented by the twisted wires in advance thereof, so 90 that there will, as shown in Fig. 5, be a snug fit of the top and bottom faces of each mortise to the curved surfaces of the twisted wires. 95

The head of the barrel is composed of two laterally separable members 4 and 5, whose central or meeting edges are rabbeted, as shown by dotted lines in Figs. 2 and 3, and whose peripheral portions are grooved, as shown at 6, in Fig. 3. The meeting portions 100 of the members 4 and 5 of the barrel head are recessed, as shown at 7, for the reception of a cam 9 which is secured to or forms part of a batten 10 on the outside of the head and a plate 11 on the inside of the head, 105 whereby said cam structure is vertically confined to the members of the head but is free to turn thereon.

When the cam is turned to the position shown in Fig. 3 the members of the head can 110

approach each other so that their adjoining edges will meet and the diameter of the head is thereby contracted to such an extent that it can be readily introduced into or removed from the barrel. When, however, the cam 9 is turned to the position shown in Fig. 2 said members are forced apart and the grooved periphery of the head is caused to engage with the inner of the pair of wires 10 with which the end portions of the staves are interwoven, the head being thereby securely locked to the barrel so as to resist either pressure from the outside tending to force it into the barrel or pressure from the inside tending to force it out of the barrel.

By preference, the staves are concave on their inner faces as shown in Fig. 4, and the central portion of each inner wire, bridging this concave, will, therefore, occupy a position some distance inward from the inner face of the stave and will provide a better hold for the grooved periphery of the barrel head than it would if it laid snugly against the inner side of the stave.

25 The peripheral portion of the barrel head is of such thickness as to be flush with the ends of the staves and thus provides backing or support for said staves, up to the ends of the latter, as shown in Fig. 2, but 30 the outer face of the head is recessed, up to a point adjacent to the periphery, as also shown in Fig. 2, the purpose of this recess being to lighten the head and to prevent the cam-operating batten 10 from projecting beyond the head.

By preference, the batten occupies a position at right angles to the joint between the members of the head when the latter are contracted, as shown in Fig. 3, and parallel 40 with said joint when the members are expanded, as shown in Fig. 2, the batten then serving to close the gap between the outer portions of the rabbeted joint and thus preventing any leakage which might otherwise 45 take place at said joint. This, however, is simply in the nature of an added precaution, since the rabbeted portions of the joint are intended to overlap sufficiently to prevent leakage under normal circumstances.

50 The batten 10, on the outside of the head, and the plate 11, on the inside of the head, effectually prevent leakage through the recesses 7 in the opposite members of the head when said members are expanded. When it 55 is desired to seal the barrel, such sealing can be readily effected by securing the batten in the locking position shown in Fig. 2 by driving a nail or screw through the batten and into one of the members of the head 60 and then applying a seal of any desired character to the head of said nail or screw, or suitable staples, one on the batten and the other on one of the head members, may be connected by a wire whose ends are secured by the usual lead seal, or other equiva-

lent means of sealing the batten in the locking position so that it cannot be moved from such locking position without breaking the seal, may be adopted.

When the proper number of staves to 70 form the barrel have been interwoven with the pairs of wires, each pair of wires is twisted together at the edges of the end staves of the series, as shown at 19, in Fig. 4, and, in order to hold the interwoven staves and wires in position to form the barrel, it is necessary that these twisted ends of the wires should be securely retained. For this purpose I prefer to employ, in connection with each pair of wires, a device of 75 the character shown in Figs. 1, 4 and 6, this device consisting of a plate 12 preferably of sheet metal which lies snugly against the outer faces of a pair of adjoining staves, this plate having a central opening 13 there- 80 in and having its end portions struck-up to form loops 14 for straddling the wires on the outer sides of the staves. The plate also has, above and below the central opening 13, other loops 15 struck-up therefrom, as 85 shown in Fig. 6, these loops providing 90 bearings for the pintles of a pair of swinging jaws 16, which can thus be introduced into position from the back of the plate and are free to swing in the central opening of 95 the latter. Each of the jaws 16 has its inner edge notched or recessed as at 17 so as to provide an opening for the reception of the twisted portions 19 of the wires 2.

As the plates 16 are swung outwardly 100 from the plate 12 the size of the opening formed by the notches 17 gradually increases and as the plates swing inwardly the size of said opening gradually decreases, the opening being at its smallest when the 105 jaws 16 are parallel with the plate 12, as shown in Figs. 4 and 6. If, therefore, the twisted portions 19 of the wires are drawn through the notches of the jaws 16 when the latter are swung outward and the jaws 110 are then pushed inwardly, they will grip the twisted portions of the wires after the manner of a toggle and the inward pull or strain upon the twisted wires will serve to maintain or increase the grip of the jaws 115 thereupon.

In order to dispose of the free ends of the twisted wires 19, the latter may be passed under spring tongues 20 struck-up from the loops 14 at the ends of the plate 12, as 120 shown in Fig. 4. The twisted ends of the wires may be readily sealed by sealing material applied to the same outside of the clamping jaw 16.

Instead of using a duplex retainer having 125 a pair of clamping jaws 16, as shown in Fig. 6, I may, in some cases, use a single retainer having but one clamping jaw 16, as shown for instance in Fig. 7, both of the twisted wires 19 in this case being retained by the 130

single spring tongue 20 at one end of the retainer.

I am aware that it has heretofore been proposed to construct a barrel having staves 5 with meeting edges, said staves being interwoven with pairs of wires twisted between the staves and occupying mortises formed in the meeting edges of the staves, but in such barrel the mortises and the twisted portions 10 of the wires do not bear such relation to one another that the twisted portions of the wires completely fill the mortises and prevent leakage of powdered material through the same.

15 I do not herein claim the construction of the expansion head, or the combination of the same with the barrel, nor do I claim the construction of the retainer for the twisted ends of the wires.

20 I claim:

1. A barrel consisting of closely fitting staves having mortised edges, said staves being interwoven with pairs of wires which are twisted between the staves, the twisted 25 portions of the wires being located in the mortised portions of the staves and com-

pletely filling said mortises, thereby preventing leakage between the staves.

2. A barrel consisting of closely fitting staves having mortised edges, said staves 30 being interwoven with pairs of wires which are twisted between the staves, all of the twists being in the same direction, and the twisted portions of the wires being located in the mortised portions of the staves and 35 completely filling said mortises, thereby preventing leakage between the staves.

3. A barrel comprising a series of closely fitted staves having mortised edges, said staves being interwoven with pairs of wires 40 which are twisted between the staves, the twisted portions of the wires occupying and completely filling the mortises in the staves and the wires being under such tension as to indent or bite into the bases of the mortises. 45

In testimony whereof, I have signed my name to this specification, in the presence of two subscribing witnesses.

EDWARD W. ROBINSON.
